FOREIGN PATENT DOCUMENTS

FR 2675167 A1 10/1992

Primary Examiner — Mary Ann Calabrese(74) *Attorney, Agent, or Firm* — Dorsey & Whitney LLP(57) **CLAIM**

The ornamental design for an instructional and figurative sign, as shown and described.

DESCRIPTION

FIG. 1 is an isometric view of an instructional and figurative sign with insert and banner showing my design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines in FIGS. 1-7 illustrate portions of the sign and form no part of the claimed design.

1 Claim, 5 Drawing Sheets(56)
